UNITED STATES PATENT OFFICE

102,854

DESIGN FOR A TEXTILE FABRIC

Eugene Irving Hanson, New York, N. Y.

Application August 13, 1936, Serial No. 64,382

Term of patent 3½ years

To whom it may concern:

Be it known that I, Eugene Irving Hanson, a citizen of the United States of America, residing in New York city, county and State of New York, have invented a new, original, and ornamental Design for a Textile Fabric, for which the following is a specification, reference being had to the accompanying drawing, forming part

thereof, wherein the figure is a plan view of a textile fabric showing my new design, in which a unit of design has been outlined in dot and dash lines.

I claim:

The ornamental design for a textile fabric substantially as shown and described.

EUGENE IRVING HANSON.
